CLAIM

The ornamental design for a monitor for laptop computer, as shown and described.

DESCRIPTION

FIG. 1 is a front perspective view of a monitor for laptop computer, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 4;

FIG. 11 is an enlarged view of the encircled portion 11 in FIG. 8;

FIG. 12 is another front perspective view thereof unfolded in an alternate configuration;

FIG. 13 is a front perspective view of FIG. 1, shown with unclaimed environmental structure;

FIG. 14 is a front perspective view of FIG. 12, shown with unclaimed environmental structure; and,

FIG. 15 is an enlarged view of the encircled portion 15 in FIG. 5.

The even-dash broken lines in FIGS. 1, 3-8, 10-15 illustrate portions of the monitor for laptop computer and form no part of the claimed design. The even-dash broken lines, showing a laptop computer in FIGS. 13-14 illustrate environment that forms no part of the claimed design. The dot-dot-dash (Continued)

broken lines encircling portions of the design in FIGS. 1, 4, 5, 8-11, 15 represent the extents of the detail views and form no part thereof.
